UNITED STATES PATENT OFFICE.

THOMAS MANAHAN, OF NEW YORK, N. Y.

GARMENT-BAG.

1,319,529.

Specification of Letters Patent.

Patented Oct. 21, 1919.

Application filed July 24, 1919. Serial No. 313,083.

To all whom it may concern:

Be it known that I, THOMAS MANAHAN, a citizen of the United States, and a resident of New York, in the county of New York and State of New York, have invented certain new and useful Improvements in Garment-Bags, of which the following is a specification, taken in connection with the accompanying drawings.

10 My invention relates to garment bags and more particularly to one which can be cheaply manufactured and which will be practically air tight and vermin proof.

15 My invention further relates to certain details of construction and combinations which will be more fully hereinafter described in the specification and set forth in the claims.

20 The accompanying drawings, referred to herein and constituting a part hereof, illustrate one embodiment of the invention, and together with the description, serve to explain the principles of the invention.

25 Figure 1 is a perspective view partly broken away for purposes of clearer illustration;

30 Fig. 2 is a view substantially on the line 2, 2 of Fig. 1 looking in the direction of the arrows, but showing the bag closed by the split sealing tube;

Fig. 3 is a horizontal section taken substantially on the line 3—3 of Fig. 1 looking in the direction of the arrows;

35 Fig. 4 is a perspective view partly broken away of the split sealing tube; and

Fig. 5 is a perspective view of the preferred form of reinforcing member which I employ.

40 In garment bags now on the market it is customary to fold down and seal the front flap of the bag, and secure within the fold a bamboo reed to give reinforcement and rigidity to the bag. It is found, however, that by sealing down one of the flaps a perfect closure cannot be obtained, permitting dust to work into the bag and also permitting insects or vermin to reach the garment.

45 By my invention I make a cheaper and more efficient bag in that I do away with the necessity of using a reed or rod, which adds materially to the expense of the bag, and I form a bag with a tighter closure. In my bag the front flap is free or unse-

cured, so that coacting with the rear flap it will, when folded over and held by the split 55 sealing tube, make a much better and tighter closure than is permitted in the bags which now employ a reed held in place by turning over and sealing the front flap of the bag.

60 I obtain the required rigidity and reinforcement by securing a reinforcing member to the back of the bag, preferably on the inside, and secure it in its proper position by means of the hooks for supporting the garment within the bag.

65 In the drawings, 1 is my improved garment bag formed of the front 2, rear 3 and ends 4 and 5. The front 2 is provided with a free flap 6, which is unsecured. The back 70 of the bag is provided with the flap 7. Mounted on the back 3 and preferably within the bag I locate my reinforcing member 8 which is preferably of heavy cardboard and is preferably of substantially the width 75 of the bag so as to give strength and rigidity to the bag. This reinforcing member is held in its proper position by means of the garment hooks 9, 9, which extend through it and through the metal plate 10 to which 80 the holding hook 11 is secured. The ends 12 of the hook 9 are bent down so as to secure the reinforcing member 8, the back 3 of the bag, and the metal plate 10 together.

85 I preferably, though not necessarily, reinforce the ends of my back by strips of fabric 13.

90 It will be seen that my bag has a neat appearance, will open readily, that it is strong and durable, has the required rigidity to insure that it will not buckle, and that when the two flaps 7 and 6 are folded over, as in Fig. 2 and are secured by the sliding split tube 14 they insure practically an air tight closure and one which will prevent either 95 dust or vermin reaching the garment within the bag.

Having thus described this invention in connection with an illustrative embodiment thereof, to the details of which I do not desire to be limited, what is claimed as new and what is desired to secure by Letters Patent is set forth in the appended claims.

100 What I claim is:—

1. The combination in a garment bag of a 105 reinforcing strip and hooks to hold the gar-

- ment within the bag, said hooks securing the reinforcing strip to the bag.
2. The combination in a garment bag of a reinforcing strip mounted within the bag and hooks to hold the garment within the bag, said hooks securing the reinforcing strip to the bag.
3. The combination in a garment bag of a reinforcing paper strip extending substantially the width of the bag, and mounted within the bag to give it strength and rigidity, and hooks to hold the garment within the bag; said hooks securing the reinforcing strip to the bag.
- 10 4. The combination of an air tight and vermin proof garment bag having the front flap turned down and unfastened to the bag, a reinforcing strip extending substantially the width of the bag to give it strength and rigidity, and hooks to support the garment in the bag, said hooks securing the reinforce-
- 15
- 20
- ing strip to the bag, and a sliding split tube to slide over both free ends of the bag and form an air tight seal protecting the garment from dust and vermin. 25
5. The combination of an air tight and vermin proof garment bag having the front flap turned down and unfastened to the bag, a reinforcing strip of paper extending substantially the width of the bag to give it 30 strength and rigidity, and located on the inside of the back of the bag, and hooks to support the garment in the bag, said hooks securing the reinforcing strip to the bag, and a sliding split tube to slide over both 35 free ends of the bag and form an air tight seal protecting the garment from dust and vermin.

THOMAS MANAHAN.
